UNITED STATES PATENT OFFICE

RICHARD SCHEIBE, OF KLOTZSCHE, NEAR DRESDEN, GERMANY

SUPERSTRUCTURE FOR RAILWAYS

Application filed July 9, 1929, Serial No. 376,894, and in Germany June 1, 1929.

My invention relates to railway roadbeds and has for its principal object to provide a new and improved construction for electrically insulating the rail from the sleeper thus making it apt to serve as an electrical conductor for signalling and other purposes.

In carrying out my invention I am aware that the principal difficulty to be overcome is that no insulation will last when the slightest relative movement occurs between the rail and the sleeper or its fastening means. For every such movement would cause friction and destroy any insulating matter within a short time whatever material it may consist of.

I therefore use a superstructure for railways the parts of which do not move under the influence of the external forces applied to them but remain substantially rigid in their relative positions. Obviously no friction can occur between the parts of such a structure and therefore no undue stress would be exerted upon insulating matter brought between the rail and its adjacent parts, because they are subject to pressure alone and any grinding effect would need pressure in coaction with movement.

Such a superstructure I have disclosed in my U. S. Patent 1,515,867. By the combination of an elastically yielding sleeper with a thoroughly rigid connection of the rail with the said sleeper the shocks are wholly absorbed by the yielding sleeper which alters momentarily its shape and pass through the means for attaching the rail as if these were one solid body. I can therefore interpose between the rail and its adjacent parts insulating matter.

In the drawings forming a part of this specification:

Fig. 1 is a cross section through the rail and head of the sleeper.

Fig. 2 is a similar view showing another embodiment of my invention.

Fig. 3 is an end elevation of the sleeper.

Fig. 4 is a diagrammatic view showing the manner in which the shocks and forces received by the rail are transmitted through the sleepers and distributed thereby over a continuous supporting area.

Fig. 5 is a top plan view of the sleeper.

Referring to Fig. 1 the numeral 1 designates the rail, 2 the insulating matter and 3 the plane upper middle part of the sleeper upon which the base of the rail rests. A bolt or screw 4 with an elongated head presses by means of a nut the clamp 5 with its one end against the base of the rail and with its other end against the sleeper. The bolt is of such thickness and is situated so near the base of the rail that an extraordinary tension can be exerted by the same upon the clamp, the measurements of which are chosen in accordance. If for instance a tension of 15000 kg. lies within the elastical capacity of the bolt and of the clamp likewise these parts will not give way in the slightest to the occurring shocks but will pass them undiminished to the sleeper. The insulating material, therefore, need only withstand a certain pressure as it will not be subject to any grinding action.

Whilst in Fig. 1 the layer of insulating material follows the upper curve of the edge of the rail base it is shown in Fig. 2 only covering the flat upper surface of the base besides of course the bottom layer. The clamp equally only touches the said upper surface of the base. The pressure exerted by the bolt is such as to prevent alone any lateral displacement of the rail the lateral shocks amounting at the most to approximately 5000 kg. It is of advantage that with this embodiment of my invention the insulating material be used only in flat layers without any bends which could cause fractures or cracks, thereby deteriorating the insulating capacity.

As shown in Fig. 3 of the drawing, a sleeper embodying my invention comprises the plane upper middle or head parts 3, on which the foot or base of the rail 2 rests.

The plane head part 3 of the sleeper merges into the side walls 13 which are of substantially cylindrical shape and extend a distance approximately equal to or slightly less than 65° of a circle starting from the point where the plane upper wall terminates. At their lower extremities the cylindrical side walls 13 merge into plane sections 14 substantially tangent to the lowest points of the cylindrical side walls and extending downwardly

therefrom preferably at an inclination of 1:4.

By referring to Fig. 4, it will be seen that this construction will ensure that the shocks and stresses caused by the traffic will be transferred to the ballast so as to be dispersed over the greatest possible surface and what is more essential that no unstressed portions or intervals will be left in the earth works between adjacent sleepers. According to the well known principle of engineering, it will be obvious that the forces which will be transmitted by a sleeper having the elastic properties as herein disclosed, will be normal to the curvative thereof at any particular point. It will therefore be seen that theoretically the downward forces transmitted to the earth works by a sleeper constructed as shown in Figs. 3 and 4 would begin just below the dot and dash line A—B (Fig. 3) and as indicated by the lines C in Fig. 4. Practically, however, the theoretical reactions transmitted by the sleeper between the lines C and D, Fig. 4, may be disregarded as they would have but little or no deteriorating effect upon the earthworks because of the slight degree of the deformations of the sleeper between these lines. Considering therefore those portions of the sleeper whose deformations are the greater and by which practically the full strength of the forces to which the sleeper is subjected are transmitted to the earth works, it will be obvious that these forces are transmitted by those portions of the sleeper situated between the lines D and E in Fig. 4. With the sleepers spaced as indicated diagrammatically in this figure it will be seen that the lines D intersect at the point F on the line G H so that therefore a continuous supporting area for the rails is formed along this line G H which it will be noted is located quite close to the rails and that there are no unstressed portions along this area between the sleepers.

It will be noted that the gap 15 between the edges of the inclined portions 14 is very small so as to leave no unstressed portion upon the earth works and also to prevent the ballast from forcing its way upwardly into the interior of the sleeper, and thus cause the interior of the sleeper to be filled up to such an extent that the under face of the top plane portion 3 would rest directly upon the ballast, and thus not only prevent the yielding effect of the sleeper, but by producing a pressure against the interior of the sleeper cause the gap 15 to be increased.

The sleeper is preferably provided as shown in Fig. 5 upon its upper portion 10 with one or more elongated slots 16 adjacent the point where the rails are to rest and if desired this portion of the sleeper may be made of somewhat thicker construction than the other portions thereof, in order to compensate for the weakening of the structure

due to the presence of the slots 16. These slots receive the heads of bolts 4.

As a result of the elastic support given by the underlying portions 13 and 14 to the head portion 3 of the sleeper, an absolutely rigid connection may be made by the fastening means described between the head portion 3 and the rail, preventing any independent movements between the two, whereby the insulating material will always be protected against shifting motion and disintegration. 75

After the sleepers have been placed in position and the rails attached thereto, ballast or soil is inserted into the interiors of the sleeper from the ends thereof, it being understood that a space is left between the top portion 3 of the sleeper and the filling material to prevent a direct reaction between this top portion and the filling which as heretofore set forth would entirely destroy the elastic effect of the sleeper. When the interiors of the sleepers are filled as described, it will be obvious that a considerable weight is represented by each sleeper which is of great value in securing a substantial construction. 90

Having thus described my invention what I claim as new and desire to secure by Letters Patent of the United States is:

1. In a support for railway rails, an elastically yielding sleeper comprising a rigid top portion and a resilient base portion, clamps for holding the rail on the sleeper, layers of electrically insulating material between the rail and those parts which would otherwise touch its surface, means for causing the clamps to exert such pressure on the rail and the interposed insulating material as to withstand by that pressure alone lateral shocks applied by the rolling stock and transmitting the said shock undiminished in strength to the sleeper. 100

2. In a support for railway rails, a yielding sleeper comprising a rigid top portion and a resilient base portion, means engaging the sleeper adapted to exert pressure for holding the rail on the sleeper, electrically insulating material between the rail and those parts which would otherwise touch its surface, and means for exerting pressure on the aforesaid interengaging parts whereby lateral shock on the rail is transmitted undiminished in strength through the insulation to the sleeper. 115

In testimony whereof I have signed my name to this specification on the 8th day of June, 1929. 120

RICHARD SCHEIBE.
